Fig. 1

Fig. 2

Fig. 4

FIG. 1 is a front perspective view taken from one side of a bow eye showing my new design;

FIG. 2 is an elevational view of the opposite side thereof;

FIG. 3 is a top plan view thereof; and

FIG. 4 is an enlarged fragmentary view of one side thereof, as outlined in FIG. 1, taken slightly in perspective, showing the rear end of the bow eye.

The dominant features of my design reside in the full-line portions of the drawings.

I claim:

The ornamental design for a bow eye, substantially as shown and described.
